UNITED STATES PATENT OFFICE.

ALFRED H. WILLETT, OF NEW YORK, N. Y., ASSIGNOR TO AMERICAN ARCH COMPANY,
OF NEW YORK, N. Y., A CORPORATION OF NEW YORK.

ARCH-BRICK.

1,103,236.

Specification of Letters Patent. Patented July 14, 1914.

Application filed September 14, 1911. Serial No. 649,245.

To all whom it may concern:

Be it known that I, ALFRED H. WILLETT, a citizen of the United States, residing at New York city, in the county of New York and State of New York, have invented certain new and useful Improvements in Arch-Brick, of which the following is a specification.

This invention has reference to an improved form of arch brick for use in fire boxes and particularly where the brick is to be placed between a water tube or other equivalent support and a side wall or sheet as is common with a portion of the bricks used in most locomotive arches.

The objects of my invention is the provision of an improved construction of brick of this character which will fit securely between the supporting tube or equivalent member and the side sheet, even although the tube may be curved or bent or irregular in shape and therefore has a relation to the side sheet which may vary considerably under different conditions of service.

In order that my invention may be better understood, I will now proceed to describe the same in connection with the accompanying drawings in which I have illustrated my improvement in various figures, of which Figure 1 is a top view of my improvement, Fig. 2 is an inverted or bottom plan view; Fig. 3 is a side elevation and Fig. 4 an end view, while Fig. 5 illustrates a view in perspective showing my improved brick as applied in position between a water tube and a side sheet.

Referring now more particularly to Fig. 5, it will be seen that I have therein indicated a short piece of bent tubing 6, the curvature of which is exaggerated in order to more clearly illustrate the improvement. Upon this tubing rests the brick 7 in inclined position, leaning at its outer edge against the side sheet 8 in the manner shown and bearing at the side sheet against the middle point 9 opposite the tube support. The support is by means of the two projecting corners or lug ends 10 which are arranged at or adjacent the edges of the brick 50 so as to place them as far apart as possible and between the two projecting corners or supporting lugs 10 there is provided a material clearance or cut away portion 11 to accommodate the curvature of the tube or to

adapt the brick to rest securely upon its three points of support even under irregular conditions.

Having thus described my invention and illustrated its use, what I claim as new and desire to secure by Letters Patent is the following:

1. An arch brick having at one end adjacent the center of the brick a projecting one point bearing for engaging a side sheet, and having at the other end a corner bearing at each side of the brick for engaging a tube with the portion intermediate the corner bearings cut away to clear the tube between such bearings.

2. An arch brick having on one side a one-point support adapted to rest against the side sheet and having its opposite side recessed to provide two spaced points of support adapted to rest upon an arch tube, so that the tube supported side is adapted to fit tubes of varying curvature, substantially as described.

3. An arch brick constructed to be supported between a tube and side sheet and having at one end two points of support adjacent the side edges of the brick with a clearance space between whereby the brick is out of contact with the tube between the side edges of the brick and having at the other end a single point of support intermediate the side edges for engaging the side sheet.

4. An arch brick constructed to be supported between a tube and side sheet and having the lower corner of the brick at one end cut away intermediate the side edges to clear the tube and permit the brick to engage the tube adjacent the corners of the brick, and having at the other end a single point of support intermediate its side edges for engaging the side sheet.

5. A locomotive furnace arch brick having a single-bearing side-sheet-engaging side and a two-bearing arch-tube-engaging side opposite said single-bearing side, said two bearings being located adjacent the ends of the brick, substantially as described.

In testimony whereof I have hereunto signed my name in the presence of the two subscribed witnesses.

ALFRED H. WILLETT.
